The ornamental design for a toilet mat as shown and described.

DESCRIPTION

FIG. 1 is a perspective view of the toilet mat embodying the new design.

FIG. 2 is a top view thereof.

FIG. 3 is a bottom view thereof.

FIG. 4 is a front view thereof.

FIG. 5 is a rear view thereof; and,

FIG. 6 is a right side view thereof, the left side being a mirror image thereof.

The figures show features in broken lines that do not form any part of the claimed design. The broken lines immediately adjacent the solid line portions of the design form the boundary of the design, with the broken lines forming no part of the claimed design.
